DISPENSING DEVICE FOR GRANULATED MATERIAL

Raymond E. Ponder, St. Louis, Mo.

Application February 23, 1951, Serial No. 14,310

Term of patent 3½ years

(Cl. D52—2)

To all whom it may concern:

Be it known that I, Raymond E. Ponder, a citizen of the United States, residing in the city of St. Louis, State of Missouri, have invented a new, original, and ornamental Design for a Dispensing Device for Granulated Material, of which the following is a specification, reference being had to the accompanying drawing, forming a part thereof.

In the drawing:

Fig. 1 is a plan view of a dispensing device for granulated material, embodying my new design;

Fig. 2 is a front elevational view thereof;

Fig. 3 is a side elevational view thereof;

Fig. 4 is a rear elevational view thereof;

Fig. 5 is a bottom plan view of the base portion of the dispensing device.

I claim:

The ornamental design for a dispensing device for granulated material, substantially as shown.

RAYMOND E. PONDER.
